UNITED STATES PATENT OFFICE

108,977

DESIGN FOR A RADIO RECEIVER CABINET

Vernon A. Kamin, Maywood, Ill., assignor to Corona Radio & Television Corporation, Chicago, Ill., a corporation of Illinois

Application March 26, 1937, Serial No. 68,414

Term of patent 3½ years

To all whom it may concern:

Be it known that I, Vernon A. Kamin, a citizen of the United States, residing at Maywood, in the county of Cook and State of Illinois, have invented a new, original, and ornamental Design for a Radio Receiver Cabinet, of which the following is a specification, reference being had to the accompanying drawing, forming a part thereof.

The drawing is a perspective view of a radio receiver cabinet, embodying my new design. The side of the cabinet not seen in the drawing is similar to the side which is shown.

The characteristic features of my design are indicated in solid lines on the drawing.

I claim:

The ornamental design for a radio receiver
cabinet, as shown and described.

VERNON A. KAMIN.
